UNITED STATES PATENT OFFICE.

EMILE MAERTENS, OF PHILADELPHIA, PENNSYLVANIA, ASSIGNOR TO
EMILE SCHEPPERS AND EDWARD SCHEPPERS, OF SAME PLACE.

DESIGN FOR WOVEN FABRICS.

SPECIFICATION forming part of Design No. 11,618, dated January 27, 1880.

Application filed November 10, 1879. Term of patent 3½ years.

To all whom it may concern:

Be it known that I, EMILE MAERTENS, of Philadelphia, Pennsylvania, have produced or invented a new and useful original Design for 5 a Woven Fabric, of which the following is a specification.

My design for a woven fabric is fully shown in the accompanying drawing, which represents an exaggerated view of a piece of the fabric.

The design comprises alternating parallel stripes *a* and *b*, the former being closely woven, and the latter of an open-work or lace-like character. The stripe *a* has an appearance resembling "momie" cloth, and the stripe *b* is made up of spaced wefts and two parallel lines of twisted warps arranged closely side by side.

Irrespective of the colors employed, I claim—

The design for a woven fabric, said design comprising the closely-woven or momie-cloth stripe *a* and the open-work stripe *b*, composed of spaced wefts and two parallel lines of twisted warps, arranged closely side by side, substantially as described, and as shown in and by the accompanying drawing. 20 25

In testimony whereof I have signed my name to this specification in the presence of two subscribing witnesses.

EMILE MAERTENS.
